United States Patent Office

Des. 201,815
Patented Aug. 3, 1965

201,815

SNOW VEHICLE

Leonard E. Greenberg, 195 Brewster Road,
West Hartford, Conn.

Filed Mar. 2, 1965, Ser. No. 84,049

Term of patent 14 years

(Cl. D34—15)

FIG. 1

FIG. 2

FIG. 3

FIG. 4

FIG. 5

FIG. 6

I claim:

The ornamental design for a snow vehicle, as shown.
